UNITED STATES PATENT OFFICE

160,556

COMBINED BASE AND CONDIMENT SHAKER
UNIT

Robert W. Smith, Rockford, Ill.

Application May 8, 1948, Serial No. 146,250

Term of patent 3½ years

(Cl. D44—22)

To all whom it may concern:

Be it known that I, Robert W. Smith, a citizen of the United States, residing at Rockford, in the county of Winnebago and State of Illinois, have invented a new, original, and ornamental Design for a Combined Base and Condiment Shaker Unit, of which the following is a specification, reference being had to the accompanying drawing, forming a part thereof.

In the drawing:

Figure 1 is a perspective view of a combined base and condiment shaker unit, showing my new design.

Fig. 2 is a plan view; and

Fig. 3 is a sectional view thereof taken on the line 3—3 of Fig. 2.

The dominant features of the design reside in the parts drawn in full lines as shown.

I claim:

The ornamental design for a combined base and condiment shaker unit, substantially as shown.

ROBERT W. SMITH.
